CLAIM

The ornamental design for a suction lifter, as shown and described.

DESCRIPTION

FIG. 1 is a right side view of a suction lifter, the left side view being a mirror image thereof, showing our new design; FIG. 2 is a right side view of a suction lifter shown in a second configuration, the left side view being a mirror image;

FIG. 3 is a front view of a suction lifter as shown in FIG. 1; FIG. 4 is a rear view thereof;

FIG. 5 is a top view thereof;

FIG. 6 is a top view, showing a third configuration; and, FIG. 7 is a bottom view of a suction lifter as shown in FIG. 1.

The broken lines depicting the bounds of the claimed design and the areas within the broken lines form no part of the claimed design.

1 Claim, 4 Drawing Sheets
